UNITED STATES PATENT OFFICE.

ALBERT J. THORNLEY, OF PAWTUCKET, RHODE ISLAND, ASSIGNOR TO
NARRAGANSETT MACHINE COMPANY, OF PAWTUCKET, RHODE ISLAND,
A CORPORATION OF RHODE ISLAND.

DESIGN FOR A DOOR AND DOOR-FRAME OF LOCKERS.

No. 38,666.

Specification for Design.

Patented July 9, 1907.

Application filed March 6, 1907. Serial No. 360,989. Term of patent 14 years.

To all whom it may concern:

Be it known that I, ALBERT J. THORNLEY, a citizen of the United States, residing at Pawtucket, in the county of Providence and State of Rhode Island, have invented a new, original, and ornamental Design for the Door and Door-Frame of a Locker, of which the following is a specification, reference being had to the accompanying drawing, forming part thereof.

The figure in the drawing represents the door and door frame of a locker, showing my new design.

I claim

The ornamental design for the door and door frame of a locker, as shown.

ALBERT J. THORNLEY.
